UNITED STATES PATENT OFFICE.

LUIS M. ORTIZ AND SMITH E. GILMORE, OF CHAMA, NEW MEXICO.

SALT AND PEPPER SHAKER.

Application filed June 3, 1921. Serial No. 474,611.

To all whom it may concern:

Be it known that we, LUIS M. ORTIZ and SMITH E. GILMORE, both citizens of the United States, and residents of Chama, in the county of Rio Arriba and State of New Mexico, have invented a new and useful Improvement in Salt and Pepper Shakers, of which the following is a full, clear, and exact description.

10 Our invention relates to receptacles for holding granular comestibles, such as salt, pepper, and the like, and it consists in the combinations, constructions, and arrangements herein described and claimed.

15 An object of our invention is to provide a two-compartment shaker having a novel means for controlling the passage of the substances placed in the compartments from the compartments, whereby the substances

20 may be taken selectively from either compartment while the other compartment is maintained in closed condition.

A further object of our invention is to provide a device of the character described 25 that is particularly adapted for use in connection with picnics or like excursions and for inclusion in any kit where it is important to keep the number of articles carried at a minimum.

30 A further object of our invention is to provide a salt and pepper shaker that combines in one article two articles ordinarily manufactured separately.

A further object of our invention is to 35 provide a combination salt and pepper shaker having two compartments, one adapted for holding salt and the other adapted for holding pepper, each of said compartments being kept normally closed to prevent extrinsic or foreign matter from entering the compartment.

Other objects and advantages will appear in the following specification, and the novel features of the invention will be particularly pointed out in the appended claim.

Our invention is illustrated in the accompanying drawings, forming part of this application, in which—

Figure 1 is a side elevation of the device,

Figure 2 is a top plan view of the same,

Figure 3 is a section along the line 3—3 of

Figure 2,

Figure 4 is a plan view of a portion of the device, and

Figure 5 is a plan view of another portion of the device.

In carrying out our invention, we provide a casing or cellar body 1 that is conventional in appearance and is formed of any suitable material, preferably glass. The 60 cellar body 1 has a vertically extending partition 2 that is substantially diametrically disposed and is formed integrally with the walls of the cellar body, thereby providing two separate similar compartments 3 and 4. 65 Each of the compartments 3 and 4 is open at the upper end of the cellar and closed at its lower end. A cap 5 is fitted upon the open upper end of the cellar body 1, the outer wall of the latter being reduced at 6 70 to frictionally engage with the cap and to define an annular shoulder 7 against which the lower end of the cylindrical portion of the cap abuts.

The cap 5 is provided with a slot 8 in 75 its cylindrical portion at the lower end of the latter and this slot engages a guide lug 9 integral with the cellar body and projecting laterally thereof so that inwardly projecting portions 10 and 11 of the cylindrical portion of the cap enter recesses or notches 12 and 13 respectively in the outer wall of the cellar body adjacent to its open upper end. In this position, the portion of the cap overlying one of the compartments 80 is perforated by a plurality of openings 14 of relatively small size and the portion of the cap overlying the other compartment is perforated by a fewer number of openings 15 of larger size, whereby the first 90 named compartment is adapted for holding pepper, while the second compartment is adapted for holding salt.

The cap 5 is provided with diametrically opposed upstanding lugs 16—16 which are 95 vertically aligned with the partition 2 when the cap has been adjusted to the cellar body in the manner described. A pintle 17 is journaled in the lugs 16—16. A cover for the cap 5 comprises two semi-circular 100 sections 18—18, each formed with integral eyelets or sleeve portions 19—19 mounted on the pintle 17 between the lugs 16—16, whereby the sections 18—18 serve as hinge members. A torsional spring 20 disposed on the pintle 17 is arranged with its ends bearing against the under surfaces of the sections 18—18, thereby tending to move each section about the pintle 17 through 180 degrees. Each of the sections 18—18 110 is provided with a lip or lug extension 21—21 bent laterally thereof and indented at

22 adjacent to its extremity to engage with a corresponding projection 22' of the wall of the cap 5, whereby the sections 18-18 are normally held in position to cover the 5 perforated portions of the cap 5, as best seen in Figure 3. Each of the lips or lug extensions 21-21 is bent outwardly at its end or away from the contiguous wall of the cellar body so that it may be conveniently 10 moved by the pressure of the thumb when the cellar body is grasped by the hand to occasion the disengagement of the projection of the cylindrical portion of the cap 5 by the indentation of the cover section, 15 whereby the latter is moved 180 degrees by the action of the spring 20 and will then overlie the other section.

From the foregoing description of the various parts of the device, the operation 20 thereof may be readily understood. The device is particularly suitable for use on picnics, since both salt and pepper may be contained therein and will be kept in good condition when exposed to unfavorable 25 conditions. The provision of a normally closed cover for the perforated portion of the cap insures the maintenance of the substances placed in the compartments 3 and 4 in the best condition. Moisture, insects, and for- 30 eign matter of various kinds are prevented from entering the compartments. When it

is desired to remove the substance in either compartment, a slight pressure of the thumb against the proper lug 21 will disengage the latter from the cylindrical portion or latching ring of the cap 5 and the action of the spring 20 will then move the cover section 180 degrees, thereby exposing the perforated portion of the cap overlying the selected compartment. 35 40

In service, a gasket 23 will be arranged between the cap 5 and the end wall of the cellar body 1.

We claim:

A closure for a two compartment condiment container comprising a cylindrical member having a perforated closed end, and lugs projected upwardly from said end, two covers hingedly secured to said lugs and being adapted to swing independently of one another, a single spring adapted to swing said covers so that their outer surfaces abut one another, and spring clips carried by said covers and being adapted to engage with said closure to yieldingly hold said covers in closed position, whereby said spring is placed under tension, said spring being adapted to swing either of said covers, when released, into a superimposed position upon the other cover. 45 50 55
